UNITED STATES PATENT OFFICE.

FRANCIS LEVITT IMPEY, OF NORTHFIELD, ENGLAND.

SUPPORT FOR LOOSE-LEAF BOOKS.

1,414,282.

Specification of Letters Patent. Patented Apr. 25, 1922.

Application filed January 20, 1921. Serial No. 438,724.

To all whom it may concern:

Be it known that I, FRANCIS LEVITT IMPEY, a subject of the King of Great Britain and Ireland, residing at Kalamazoo 5 Works, Northfield, in the county of Warwick, England, have invented certain new and useful Improvements Relating to Supports for Loose-Leaf Books, of which the following is a specification.

10 This invention relates to supports used in conjunction with loose leaf books of the type in which a binding bar is hinged to one edge of each of the covers and in which the leaves are positioned by posts inserted into the binding bars through holes in the leaves. With the book opened out and the leaves divided into two parts which respectively rest with the covers of the book on the two parts of the support, it is found that owing 15 to tilting of the operative surfaces of the binding bars relatively to the adjacent faces of the covers and leaves inconvenience is often experienced in re-engaging the posts with the bars.

20 25 The object of the present invention is to avoid this inconvenience in a simple manner, and for this purpose the invention comprises the use with the support, of one or more trough like or equivalent sockets, holders or other retaining devices for the binding bars, which devices secure the said bars in the proper relationship with the covers and leaves of the book.

The invention also comprises the combination with the support, of means coacting with the binding bars for holding them firmly in the said retaining devices.

Referring to the accompanying sheet of explanatory drawings:—

40 Figure 1 is a diagrammatic side elevation showing a book support provided with this invention, an open book in position on the support being indicated by dotted lines.

Figure 2 is a diagrammatic plan of a portion of the support.

In carrying the invention into effect as shown, in conjunction with a support consisting of a pair of relatively inclined parts *a*, *b* on which the book covers *c* rest, and an intermediate abutment *d* against the opposite sides of which rest the adjacent edges of the leaves *e*, at or near the junction of each part *a*, *b* and the abutment is arranged a trough like holder *f*, socket or its equivalent 55 for the reception and engagement of the

binding bar *g*. By means of this device the binding bar is not permitted to move relatively to the cover or leaves and consequently the face of the binding bar is kept normal to holes in the leaves, and the securing posts 60 *h* can therefore be readily inserted. The adjacent side of the abutment may be provided with any convenient spring or other catch *i* which can be caused to engage the upper side of the binding bar and secure it 65 firmly within the trough.

When the leaves are always assembled on one side of the abutment, only one such device as that above described may be provided, this being arranged to secure the 70 clamping bar of the cover on which the leaves are superimposed.

The trough may be used in conjunction with either fixed or hinged parts for carrying the book covers. In the latter case the 75 arrangement of the trough is such that when the adjacent cover support is adjusted to the desired inclination the trough moves with it, so that there is no relative movement between the trough and the said part. 80 In Figure 1 the left hand support *a* is hingedly adjustable and the right hand side *b* is fixed.

The abutment is provided with the usual slots *j* across which can pass the thongs or 85 the like by which the covers are connected, and they may also be provided with the usual projecting pieces *k* which by entering corresponding slots in the adjacent edges of the leaves serve to locate the leaves in proper 90 relation to each other. When the catch *i* is used the said slots in the leaves give the required access for the catch to the upper surface of the clamping bar.

Having thus described my invention what 95 I claim as new and desire to secure by Letters Patent is:—

In a support for loose leaf books the combination of a pair of members on which the covers of a book are carried, an intermediate 100 abutment, trough like retaining devices on said members for the binding bars of the book covers, projections on the outer faces of the abutment adapted to enter notches in the leaves, and means sliding within said 105 projections for engaging the binding bars, substantially as described.

In testimony whereof I have signed my name to this specification.

FRANCIS LEVITT IMPEY.
